[57] CLAIM

The ornamental design for a luggage carrier, substantially as shown and described.

DESCRIPTION

FIG. 1 is a perspective view of a luggage carrier showing our new design, it being understood that the broken lines are for illustrative purposes only;

FIG. 2 is an enlarged top plan view thereof;

FIG. 3 is an enlarged side elevational view thereof;

FIG. 4 is an enlarged front elevational view thereof; and

FIG. 5 is an enlarged rear elevational view thereof.

The bottom of the luggage carrier is substantially unornamented.

UNITED STATES PATENT AND TRADEMARK OFFICE
CERTIFICATE OF CORRECTION

PATENT NO. : Des. 268,340
DATED : March 22, 1983

INVENTOR(S) : Dennis F. Otto, Vernon R. Wamsley

It is certified that error appears in the above-identified patent and that said Letters Patent are hereby corrected as shown below:

On the title page,

Under the section entitled "References Cited"
delete "250,732" and insert --D. 250,732--.

Under the section entitled "Claim", line 1, delete the comma "," after the word carrier.

Signed and Sealed this

Thirty-first Day of May 1983

[SEAL]

Attest:

DONALD J. QUIGG

Attesting Officer

Acting Commissioner of Patents and Trademarks
